TELEPHONE SUBSCRIBER SET WITH A
SPEECH CURRENT TRANSFORMER AND
A POLARIZED ALTERNATING CURRENT
ALARM

Jean Patry and Richard Strub, Zurich, Switzerland, assignors to Albiswerk Zurich A. G., Zurich, Switzerland, a Swiss company

Application June 17, 1948, Serial No. 33,525
In Switzerland June 14, 1947

7 Claims. (Cl. 179—81)

1

The invention relates to telephone substation devices which combine a speech-current transformer and a polarized alternating-current alarm to a single unit.

It is an object of the invention to devise such units in such a manner that it is capable of performing its double functions without either function impairing the other, i. e., substantially without loss in transforming efficiency and without diminution of the alarm sensitivity.

To this end, and in accordance with the invention, the transformer windings and the alarm or ringer windings are mounted on a common magnetizable core with an air gap, and the core ends adjacent the gap form also an equipolar pair of pole shoes for one pole of a polarizing magnet whose other pole carries an armature movable in the air gap. In such a device, the permanent flux and the operating flux of the coil windings overlap practically in the air gap only. Owing to the separation of permanent flux and operating flux of the exciting coil, the magnetic circuit of the coil can be designed for minimum loss, which produces favorable transforming conditions for speech-current when the exciting coil is used as a transformer.

These and other objects and features will be apparent from the following description in conjunction with the embodiments of the invention exemplified by the drawings in which

Fig. 1 shows the plan view and Fig. 2 a side elevation of a device in which a one-piece exciting coil is arranged in the longitudinal direction of the air gap; Fig. 3 shows a plan view and Fig. 4 a side elevation of another device in which a one-piece exciting coil is arranged transversely to the air gap; Fig. 5 shows an embodiment with a two-part exciting coil in which the two coil parts are arranged in symmetrical relationship to the air gap and the armature is arranged between the two coil parts; and Fig. 6 shows the wiring diagram of a telephone substation equipped with a device according to the invention.

In Figs. 1 and 2 the two arm ends 2 and 3 of the coil core 4 which are separated from each other by the air gap 1, form an equipolar pair of pole shoes of the permanent magnet 5. The arm ends are firmly screwed to a piece of soft iron 6 which is fastened to an assembly plate 7 of non-magnetizable material. The plate 7 also carries the magnet 5 and two bell domes 8 and 9 arranged eccentrically one inside the other. Attached to the other pole end of the permanent magnet are two pieces of soft iron 10 similar to pole shoes attached by screws 12 which also hold a spring member 11. A rigid armature 13

2

is welded to member 11 at point 14. The armature is therefore capable of resilient reciprocal motion within the air gap. When the coil 15, mounted on core 4, is excited by alternating current, the armature 13 is actuated and transmits its oscillations via the alarm clapper 16 to the bell domes 8 and 9.

In the device of Figs. 3 and 4 the air gap 31 is formed by the two arm ends 32 and 33 of the coil core 34 which again form an equipolar pair of pole shoes of the permanent magnet 35. This permanent magnet and the piece of soft iron 36 are secured to the assembly plate 37, which also carries the two bell domes 38 and 39. The armature 43 is made inherently resilient by weakening it at the point 44 by notches. Its end 40 remote from the air gap is broadened and rigidly connected to the second pole end 41 by the screws 42. The coil 45 is arranged transversally to the air gap and located below the polarizing magnet system. The armature, when excited, transmits its oscillations via the clapper 46 to the bell domes 38 and 39.

In the device of Fig. 5 two exciting coils 65a and 65b are arranged in symmetrical relationship to the air gap 51 and have a common iron core 54 whose two arm ends 52 and 53 form the air gap. The polarizing magnet system consists of a permanent magnet 55, a connecting piece 56 between the iron core and the permanent magnet, and an armature 63 rendered inherently resilient by notches 64. The broadened end 60 of armature 63 is rigidly connected by screws 62 to the permanent magnet 55 as in the embodiment according to Figs. 3 and 4. The arrangement of the armature between the two exciting coils gives a very compact design to the coil and permanent magnet system. A hemispherical bell dome 58 covers this whole system and is struck at a recess 59 by the clapper 66 mounted on the armature 63.

The circuit according to Fig. 6 is shown in condition to receive incoming calls. Three coil windings 101, 102 and 103 are wound in the same direction and have a common iron core 104. The two arm ends 141 and 142 of this iron core, which are separated by the air gap 140, form an equipolar pair of pole shoes of the permanent magnet 143. The resilient armature 144, which is connected to the other pole end of the permanent magnet by a piece of soft iron 145, is movable in the air gap 140.

In the illustrated condition, the direct current is cut off by a condenser 105 connected in series to the coil. When alternating alarm voltage is received across terminals 119, 110 from the exchange, the armature is excited and the sub-

scriber is alarmed. When the receiver is picked up, the hook contact 111 closes and connects the microphone 106 parallel to a circuit consisting of the series connection of winding 101 and condenser 105, while the hook contact 112 connects a circuit consisting of the series connection of receiver 107 and condenser 108 parallel to winding 102. This establishes the speech connection. The copper resistance of winding 101 and the resistance of winding 102 may be utilized for side-tone reduction. The microphone feed current, which flows through the windings 102 and 103, premagnetises the coil core 104, so that the armature is not excited by the speech currents. In the case of automatic dialling, a short-circuit connection in which the dialling impulse contact 114 is arranged, is built up in the usual way between the line connections by the short-circuit contact 113 of the dial.

The invention is also applicable for local battery systems. It is then of advantage to use a substation circuit with an auto-transformer. If no auto-transformer is used, it may be necessary to obtain the series connection of the various transformer windings for the speech currents by means of special switches, so that the exciting coil has the necessary total number of windings. The pre-magnetisation of the iron core by the microphone feed current while the telephone is in operation is always important because due to the premagnetization, the armature cannot be excited by the speech currents and hence cannot lead to distortion of the speech currents. It is also possible to place two completely separate windings on the common iron core, one serving as the exciting coil for the alarm bell while the other represents the transformer. This results in a substation circuit similar to that usual in conventional telephone set circuits.

We claim as our invention:

1. A telephone substation device, comprising a magnetizable core having an air gap, a permanent magnet having two pole ends, one of said pole ends being joined with a portion of said core which includes said air gap, said one pole end having two pole parts at the two respective sides of said air gap, a single coil unit having alarm control windings and transformer windings and being mounted on said core away from said core portion, and an armature member mounted on said other pole end and movable in said air gap.

2. In a telephone substation device according to claim 1, said core and said magnet extending in substantially parallel planes respectively, and said coil unit having an axis substantially parallel to the longitudinal direction of said armature.

3. In a telephone substation device according to claim 1, said core and said magnet extending in respective planes substantially perpendicular to each other, and said coil unit having an axis transverse to the longitudinal direction of said armature.

4. A telephone substation device, comprising a transformer core having two pole faces facing each other and having an air gap between said faces, alarm control windings disposed on said core, speech-current transformer windings also disposed on said core, a polarizing magnet having two poles, the first of said magnet poles being joined with said core and being divided into two portions bordering said respective pole faces, and an armature member mounted on the second pole and movably extending through said air gap, so

that the polarizing magnet flux due to said magnet and the variable core flux due to said windings are mutually superimposed substantially only in said air gap.

5. A telephone substation device, comprising a substantially ring-shaped transformer core having an air gap and having two end portions facing each other across said gap, a substation circuit having alarm control windings and speech-current transformer windings series connected with each other and disposed on said core away from said end portions, a permanent magnet having two pole ends, the first of said pole ends having two mutually spaced pole parts rigidly joined with said respective core end portions, the second pole end being magnetically spaced from said core, and an alarm actuating armature member mounted on said second pole end and extending through said gap, said armature being elastically movable relative to said core and magnet.

6. A telephone substation device, comprising a generally annular transformer core having an air gap and having two end portions facing each other across said gap, a permanent magnet having two pole ends, the first of said pole ends having two pole parts joined with said two respective core end portions, the second pole end being magnetically spaced from said core, two coil units comprising alarm control windings and speech-current transformer windings and being mounted on said core away from said pole parts and symmetrically with respect to said air gap, and an armature member mounted on said other pole end and movable in said air gap.

7. A telephone substation device, comprising a generally annular transformer core having an air gap and having two end portions facing each other across said gap, a permanent magnet having two pole ends, the first of said pole ends having two pole parts joined with said two respective core end portions, the second pole end being magnetically spaced from said core, a substation circuit, two coil units comprising alarm control windings and speech-current transformer windings connected in said circuit in series relation to each other, said two coil units being mounted on said core away from said core portion and symmetrical with respect to said air gap, and an armature member disposed between said two coil units, said armature member being mounted on said second pole end and extending movably through said air gap.
